UNITED STATES PATENT OFFICE.

FINESS E. NEAL, OF ANDERSON, INDIANA.

LINER FOR PNEUMATIC TIRES.

1,155,367.

Specification of Letters Patent.

Patented Oct. 5, 1915.

Application filed December 14, 1914. Serial No. 877,228.

To all whom it may concern:

Be it known that I, FINESS E. NEAL, a citizen of the United States, residing at Anderson, in the county of Madison and State of Indiana, have invented certain new and useful Improvements in Liners for Pneumatic Tires; and I do declare the following to be a full, clear, and exact description of the invention, such as will enable others skilled in the part to which it appertains to make and use the same.

My invention relates broadly to improvements in pneumatic tires and more particularly to means for preventing puncturing thereof.

The main object of the invention is to provide an extremely simple liner which may be applied between the outer casing and inner tube of practically any pneumatic tire, and to so construct this liner as to prevent puncturing of the tube. In carrying out this object, a central retaining ring is provided, and inner and outer series of curved plates are hingedly connected at their inner ends to said ring, said plates extending laterally in opposite directions from the ring and being so curved as to conform to the transverse curvature of the tire.

A further object of the invention, therefore becomes to so construct these plates, as to form the inner and outer plates which project to each side of the ring, of single and individual sheets of metal so bent as to form knuckles which pass around said ring and unite the inner and outer plates.

With the above and minor objects in view, the invention resides in certain novel features of construction and combination, herein described and claimed and shown in the drawings wherein:

Figure 1 is a side elevation, partly in section, showing the application of a portion of the liner to a portion of a tire; Fig. 2 is a vertical transverse section as seen on the line 2-2 of Fig. 1; Fig. 3 is a plan view of a portion of the liner with its covering removed; Fig. 4 is a perspective of a portion of the liner in the condition seen in Fig. 3 and showing a number of the plates separated one from the other; Fig. 5 is a detail section as seen on the line 5-5 of Fig. 3; and Fig. 6 is a plan view of one of the blanks from which the protecting plates are formed.

In these drawings, forming a part of this application, a tire casing C and an inner

tube T are shown, both of these members being of common construction. Interposed between the casing and tube, is my improved liner 1 which is constructed as hereinafter described.

The liner 1 comprises an attaching ring 2 which extends circumferentially around the tire between the tube and casing, an inner series of curved plates 3 which project laterally in one direction from the ring 2, a second inner series of curved plates 4 which project laterally from said ring in the opposite direction, an outer series of curved plates 5 which overlie the plates 3, and a second outer series of curved plates 6 which overlie the inner plates 4. As seen more particularly in Fig. 5, the centers of the plates 5 and 6 overlie the spaces between the adjacent edges of the inner plates 3 and 4 or, in other words, the outer plates break joints with the inner plates.

As most clearly seen in Fig. 4, the inner ends of the plates 3 and 5 are connected by knuckles 7 which embrace and are spaced upon the ring 2, while the plates 4 and 6 are connected at their inner edges by integral knuckles 8 which likewise embrace the ring and which are interposed between the knuckles 7. By such construction, a device is provided which will be practically puncture-proof, and which possesses no spaces through which objects might be projected to puncture the tube T.

The structure just described is preferably equipped with a split canvas tube 9 which is cemented or otherwise secured to its inner side, and with a canvas covering 10 which is secured in any suitable manner to its outer side, said covering 10, having its edges secured at 11 to the tube 9, while the latter practically encircles the tube T to protect its sides as well as its tread portion.

In order to more clearly illustrate the manner in which the inner plates 3, the outer plates 5 contacting therewith, and the knuckles 7, uniting the two are formed, Fig. 6 is provided, which figure shows a blank of metal from which these plates and knuckles, as well as the plates 4 and 6 and the knuckles 8, are formed. The two plates are then bent one toward the other around the ring 2, to form knuckles and to constitute the inner and outer protecting plates above described.

From the foregoing description, taken in connection with the accompanying draw-

ings, it will be seen that very simple structure has been provided for carrying out the objects of the invention, yet that the efficiency and durability of the liner is not impaired by such simplicity.

I claim:

A tire shield comprising a single ring and two annular series of units disposed one series on each side of said ring, each unit 10 comprising inner and outer rectangular plates of substantially equal area, one half of the width of the inner plate being overlapped by one half of the width of the outer plate, and a knuckle uniting and formed in-

tegrally with the inner ends of the overlapped halves of the plates, the knuckles of the several units being disposed end to end around the ring, and the projecting halves of all the inner plates being overlapped by the projecting halves of the outer plates of adjacent units.

In testimony whereof I have hereunto set my hand in presence of two subscribing witnesses.

FINESS E. NEAL.
